UNITED STATES PATENT OFFICE.

JOHN C. DUEBER, OF CANTON, OHIO.

DESIGN FOR A WATCHCASE.

SPECIFICATION forming part of Design No. 26,421, dated December 22, 1896.

Application filed November 9, 1896. Serial No. 611,567. Term of patent 7 years.

To all whom it may concern:

Be it known that I, JOHN C. DUEBER, a citizen of the United States, and a resident of the city of Canton, county of Stark, State of Ohio, have invented a new and useful Design for Watchcases, of which the following is a full, clear, and exact description, reference being had to the accompanying drawings, making part of this specification.

10 My invention relates to a new design for watchcases of the configuration and ornamentation shown in the accompanying drawings, in which—

Figure 1 is a view in elevation of the back of the case. Fig. 2 is a similar view of the side of the watchcase; and Fig. 3 is a similar view of the front of the case, showing the open face and dial.

The leading feature of my design consists of the center A, of gold, and the gold or silver bezel B of the front and back, the back bezel having mounted in its center a gold plate C with a white enameled center D, displaying the flag of the United States in color and any 25 desired appropriate words or mottoes. In the accompanying drawings I have shown the center A ornamented with vermicelli engraving, but this may be varied to suit the fancy. The bezel of either the front or back, or both,

and the dial which is seen through the crystal 30 of the open face may be plain or have engraved or enameled thereon any suitable or desired words or figures.

The back of the case (shown in Fig. 1) is of silver, and in the center thereof there is 35 mounted the gold plate C with a white enameled center D, upon which is displayed in colors the United States flag and upon either side thereof a five-pointed star. Above and below the flag may be painted or enameled 40 any suitable or desired words or figures. Upon the gold plate C and around the white enameled center D, above and below, are two white enameled scrolls E and F, upon or within which may be placed any suitable or 45 desired words, the whole effect being to produce in a watchcase a pleasing and desirable effect and a souvenir of historic interest.

What I claim is—

The design for a watchcase as herein shown 50 and described.

In testimony whereof I have hereunto set my hand this 5th day of November, A. D. 1896.

JOHN C. DUEBER.
